Primary Examiner—Nanda Bondade(74) *Attorney, Agent, or Firm*—Fredrikson & Byron, P.A.(57) **CLAIM**

The ornamental design for a headset, as shown.

DESCRIPTION

FIG. 1 is a front, top, right side perspective view of a headset of our invention;

FIG. 2 is a top view thereof;

FIG. 3 is a front view thereof;

FIG. 4 is a left side view thereof;

FIG. 5 is a right side view thereof;

FIG. 6 is a rear view thereof;

FIG. 7 is a bottom view thereof;

FIG. 8 is a front, top, right side perspective view of the electronic housing of the headset, show separately for clarity of illustration;

FIG. 9 is a top view thereof;

FIG. 10 is a front view thereof;

FIG. 11 is a left side view thereof;

FIG. 12 is a right side view thereof;

FIG. 13 is a rear view thereof; and,

FIG. 14 is a bottom view thereof.
